RECHARGEABLE FLASHLIGHT

William H. Doring, Old Greenwich, Conn., assignor to
Union Carbide Corporation, a corporation of New
York

Filed Dec. 19, 1963, Ser. No. 77,866

Term of patent 14 years

(Cl. D48—24)

FIG. 1

FIG. 2

FIG. 3

FIG. 4

FIG. 5

FIGURE 1 is a top plan view of a rechargeable flashlight embodying my design;

FIGURE 2 is a side elevational view thereof;

FIGURE 3 is a bottom view thereof;

FIGURE 4 is a rear view thereof; and

FIGURE 5 is a front view thereof.

I claim:

The ornamental design for a rechargeable flashlight, substantially as shown.
